Inventor:
Claude M. McCord,
By R. R. Kingsland,
His Attorney.

UNITED STATES PATENT OFFICE.

CLAUDE M. McCORD, OF RICHMOND HEIGHTS, MISSOURI, ASSIGNOR TO ARMATURE REWINDING COMPANY, OF ST. LOUIS, MISSOURI, A CORPORATION OF MISSOURI.

ARMATURE-WINDING MACHINE.

Application filed July 30, 1923. Serial No. 654,589.

To all whom it may concern:

Be it known that I, CLAUDE M. McCORD, a citizen of the United States, residing at Richmond Heights, St. Louis County, State 5 of Missouri, have invented a new and useful Armature-Winding Machine, of which the following is a specification.

This invention relates to armature winding machines.

10 An object of the invention is to provide a machine to facilitate the winding of armatures by imparting to the armature cores alternating reciprocating and rocking movements to place the wire in the core slots.

15 Another object of the invention is to provide a machine for imparting longitudinal and rocking movements to an armature core, and improved means for controlling operation thereof to effect proper timing of the 20 movement during the winding operation.

Other objects will appear from the following description reference being made to the drawing in which

Fig. 1 is a longitudinal vertical sectional view of my improved machine.

Fig. 2 is a vertical cross sectional view.

Fig. 3 is a diagrammatic view of the electric operating connections.

Fig. 4 is a detail view showing the means 30 for preventing turning of the rack which imparts axial movements to the axially movable rock shaft by which rocking and longitudinal movements are imparted to the armature core during winding thereof.

35 In the embodiment of the invention shown an axially movable rock shaft 1 is supported in bearings in the frames 2 for axial and rocking movements. One end of the shaft 1 is equipped with a chuck device 3 for engaging and supporting a cooperating member 4 on which the armature core 5 is supported. The chuck device 3 has a stem 6 extending into the shaft 1 and equipped with a collar 7 abutting against a collar 8 on the

40 shaft 1. The collar 7 is provided with a series of radial holes in its periphery adapted to receive the releasable latch bolt 9 operatively mounted in a support 10 attached to the collar 8. The end of the latch bolt 9 may be provided with a hand wheel or similar manual device 11 by which the bolt 9

45 may be withdrawn to permit the chuck to be turned to place the armature core in different positions for winding. Obviously if 50 the bolt 9 be held withdrawn during longitudinal

movement of the shaft 1 as herein-after described the chuck 3 may be manually turned during such longitudinal movement thereby turning the armature core 5 to wind the wire in skewed slots. Preferably the 60 wire 12 is passed to the armature core from above and, if desired, may be fed through a guide 13.

The mechanism for rocking the shaft 1 includes a gear 14 mounted on the shaft for 65 turning movements therewith in a manner to permit the shaft to move axially through said gear. The gear is held from axial movements by a frame member 15 having a notch into which the gear 14 is received, 70 leaving said gear 14 free to turn with the shaft 1 and leaving the shaft 1 free for axial movement while the gear 14 is held stationary. A gear 16 is supported on a shaft 17. A slotted crank arm 18 on the 75 shaft 17 receives a pin 19 on the upper end of a connecting rod 20, the lower end of which has pivotal connection 21 with a vertically movable member 22 mounted on supporting guides 23. The member 22 supports a pair of spaced rollers 24, between which a cam 25 operates to raise and to lower the member 22 and thereby impart 80 rocking movements to the shaft 17, with the result that rocking movements are also imparted to the shaft 1 and thereby to the armature core 5. The cam 25 is attached to a shaft 26 rotated by worm and gear connections 27 from a shaft 28.

The mechanism for imparting axial movements to the shaft 1 comprises a rack 29 supported by collars 30 keyed to the shaft 1 by rings 31, whereby longitudinal movement of the rack 29 will move the shaft 1 axially leaving the shaft 1 free to turn without turning the collars 30 or moving the rack 29. The collars 30 are held from turning movements by a depending flange 32 on the member 15 engaging in notches 33 (Fig. 4) in the collars 30. A gear wheel 34 on a 100 shaft 35 is in constant mesh with the rack 29. A crank arm 36 on the shaft 35 has pin-in-slot connection 37 with the upper end of a connecting link 38, the lower end of which is pivoted to the upper end of a vertically movable member 39 having slots 40 for receiving the supporting guides 41. The mounting of the member 22 is the same as that of the member 39. The member 39 supports spaced rollers 42 between which a 110

cam 43 on the shaft 26 operates to impart rocking movements to the gear 34 through which axial movements are imparted to the shaft 1 and thereby to the armature core 5.

The shaft 28 is in axial alignment with a power driven shaft 44 and the adjacent ends of the shafts 28 and 44 are equipped with clutch devices 45 preferably of the magnetic type, so that the shaft 28 may be driven by the shaft 44 optionally. Fig. 3 illustrates diagrammatically the mechanism for controlling the machine equipped with a magnetic clutch. As shown the coiled magnetic clutch 45 has one end grounded and the other end in contact with a ring 46 on the clutch member with which a brush 47 in connection with a lead wire 48 contacts. The wire 48 leads to a switch 49 from which a wire leads to a battery. A wire 50 from the battery is in connection with a brush 51 contacting with a broken ring 52 on a gear 53 and having an insulating gap 54. The ring 52 is grounded. The gear 53 meshes with and is driven by a pinion 55 on the shaft 26 so that once during each revolution of the gear 53 the circuit is broken by the brush 51 coming in contact with the insulation gap 54. The ratio between the gear 53 and the pinion 55 is such that the proper number of reciprocating and rocking movements are imparted to the armature core 5 to place thereon the proper number of windings before the brush 51 comes into contact with the insulation gap 54. When the circuit is broken by the brush 51 coming in contact with the insulation gap 54 the magnetic clutch 45 is deenergized permitting the shaft 28 and the mechanism operated thereby to stop while the shaft 44 continues to rotate. This is for the purpose of permitting the operator to release the latch device 9 and turn the armature core to position to receive the next winding. After the armature core has been adjusted the machine may be started again by closing a switch 56 having a wire 57 leading to the battery and a ground wire 58. The closing of the switch 56 energizes the magnetic clutch with the result that the shaft 28 and the mechanism operated thereby is started causing the pinion 55 to rotate the gear 53 and move the gap 54 beyond the brush 51. After the mechanism has started the operator again opens the switch 56, leaving it for the insulation gap 54 to cause the machine to stop at the proper time as before.

The cams 25 and 43 are arranged relatively so that when either cam is imparting movement to the connections controlled thereby the other cam leaves the connection controlled by it stationary. Thus when the cam 25 is actuating the connections to turn the shaft 1 in either direction the cam 43 is making an idle movement to the extent that it does not move the connections for

reciprocating the shaft 1 until after the turning movement of said shaft has stopped; which is at the time that the cam 25 moves without moving the connections controlled by it. So also when the cam 43 imparts axial movements to the shaft 1 the mechanism controlled by the cam 25 for rocking said shaft is stationary.

From the foregoing it will be seen that my invention is a distinct advance in the art of winding armatures and that the machine is thoroughly complete. The gearing 53—55 can be made in such ratio as required to impart the necessary axial and rocking movements to the armature core to receive the necessary number of windings irrespective of the variation in the number of windings of the different armatures. The reciprocating and turning movements of the armature core are effected automatically without special care or attention by the operator and when the proper number of windings are applied to the core the operating mechanism is automatically stopped.

While I have shown and described an appropriate type of machine for satisfactorily obtaining the desired results, I am aware that the construction and arrangement of the machine may be widely varied without departure from the nature and principle of the invention. Therefore, I do not restrict myself to the identical form of machine shown, but contemplate such variations as may be desired and as are within the scope of the appended claims.

What I claim and desire to secure by Letters Patent is:—

1. A machine of the character described, comprising a support for an armature core, means for holding said support in different adjusted positions for operation, and mechanism for imparting alternating longitudinal and rocking movements to said support and thereby to the armature core in all of the adjusted positions of said support.

2. A machine of the character described, comprising a support for an armature core, means for holding said support in different adjusted positions for operation, mechanism for imparting longitudinal movements to the support and thereby to the armature core to place a wire longitudinally in a slot in the core, mechanism for rocking the support to position the armature for receiving the wire in another slot, and mechanism for moving the support and the armature core longitudinally in the opposite direction to place the wire in said second slot.

3. A machine of the character described, comprising a shaft supported for axial and rocking movements, a support, means for holding said support in different adjusted positions in connection with said shaft, and mechanism for imparting axial and rocking movements to said shaft.

4. A machine of the character described, comprising a support for an armature core, means for holding said support in different adjusted positions for operation, mechanism for imparting turning movements to the support, a gear wheel, mechanism for rotating said gear wheel alternately in opposite directions, and a rack engaged by said gear wheel for imparting longitudinal movements to said support. 5. A machine of the character described, comprising an axially movable shaft, gearing for imparting axial movements to said shaft, gearing for rocking said shaft, and mechanism for operating said gearings intermittently and alternately to impart intermittent and alternate axial and rocking movements to said shaft. 6. A machine of the character described, comprising a shaft, gearing for imparting axial movements to said shaft, a cam, connections controlled by said cam for operating said gearing, gearing for imparting turning movements to said shaft, a cam, connections operated by said second cam for operating said second gearing, and a shaft for operating both of said cams. 7. A machine of the character described, comprising a shaft supported for axial and turning movements, a rack in connection with said shaft, a gear wheel for engaging said rack to move said shaft axially in opposite directions, a gear on said shaft, means for holding said gear from moving with said shaft when said shaft is moved axially, and mechanism for rotating said gear to impart turning movements to said shaft. 8. A machine of the character described, comprising a shaft, a rack supported by said shaft, a gear engaging said rack for imparting axial movements to said shaft, a gear wheel on said shaft, and mechanism for operating said gear wheel to impart turning movements to said shaft. 9. A machine of the character described, comprising a shaft supported for axial and turning movements, a rack supported by said shaft, a gear wheel on said shaft, mechanism engaging said rack to impart axial movements to said shaft, mechanism for operating said gear wheel to impart turning movements to said shaft, and means for operating said mechanism intermittently and alternately to impart intermittent and alternate axial and turning movements to said shaft. 10. A machine of the character described, comprising a shaft supported for axial and turning movements, a rack supported by said shaft, a gear wheel on said shaft, mechanism engaging said rack to impart axial movements to said shaft, mechanism for operating said gear wheel to impart turning movements to said shaft, means for operating said mechanism intermittently and alternately to impart intermittent and alternate axial and turning movements to said shaft. 11. A machine of the character described, comprising a shaft, a support for an armature core, means for holding said support in different adjusted positions in connection with said shaft, gearing for imparting axial movements to said shaft, additional gearing for imparting turning movements to said shaft, and mechanism for operating said gearings alternately and intermittently to impart alternate and intermittent axial and turning movements to said shaft. 12. A machine of the character described, comprising an element mounted for rocking and longitudinal reciprocating movements, a power driven rotary shaft, an additional shaft, means for operating the additional shaft from the rotary shaft, and separate gear mechanisms operated by said additional shaft for imparting alternating rocking and reciprocating movements to said element. 13. A machine of the character described, comprising an element mounted for rocking and longitudinal reciprocating movements, a rotary power shaft, an additional shaft, a clutch device for rotating the additional shaft from the power shaft, separate gear mechanisms operated by the additional shaft for imparting alternating rocking and reciprocating movements to said element, and automatic means for releasing said clutch device. 14. A machine of the character described, comprising an element mounted for rocking and longitudinal reciprocating movements, means for supporting and imparting alternating rocking and longitudinal movements to an armature core by said element to wind a wire in the slots of said core, a rotary power shaft, an additional shaft, a clutch device for rotating said additional shaft from said power shaft, separate gear mechanisms operated by said additional shaft for imparting alternating rocking and reciprocating movements to said element and thereby to the armature core until the winding of a section of said core is completed, and means for releasing said clutch device at the completion of the winding of each section of the armature core. 15. A machine of the character described, comprising an element mounted for reciprocating and rocking movements, gearing for rocking said element, gearing for reciprocating said element, a rotary shaft, connections operated by said shaft for operating said first-named gearing, and other connections operated by said shaft for operating said second-named gearing.

16. A machine of the character described, comprising an element mounted for reciprocating and rocking movements, gearing for rocking said element, gearing for reciprocating said element, a rotary shaft, connections operated by said shaft for operating said first-named gearing, other connections operated by said shaft for operating said second-named gearing, and means for preventing operation of each of said connections during the operation of the other of said connections.

17. A machine of the character described, comprising an element mounted for reciprocating and rocking movements, gearing for rocking said element, gearing for reciprocating said element, a rotary shaft, connections operated by said shaft for operating said first-named gearing, other connections operated by said shaft for operating said second-named gearing, and means for stopping operation of said shaft after a predetermined number of movements of said element.

18. A machine of the character described, comprising an element mounted for reciprocating and rocking movements, gearing for rocking said element, gearing for reciprocating said element, a rotary shaft, connections operated by said shaft for operating said first-named gearing, other connections operated by said shaft for operating said second-named gearing, means for preventing operation of each of said connections during the operation of the other of said connections, and means for stopping operation of said shaft after a predetermined number of movements of said element.

19. A machine of the character described, comprising an element mounted for reciprocating and rocking movements, a rotary shaft, a cam on said shaft, mechanism operated intermittently by said cam for imparting longitudinal movements to said element during different time intervals, and mechanism operated by said shaft for imparting rocking movements to said element during different time intervals between the intervals of the reciprocating movements of said element.

20. A machine of the character described, comprising an element mounted for reciprocating and rocking movements, a rotary

shaft, gear connections operated by said shaft for imparting intermittent reciprocating movements to said element at spaced intervals of time; and gear connections operated by said shaft for imparting intermittent rocking movements to said element at spaced intervals of time between the reciprocating movements aforesaid.

21. A machine of the character described, comprising an element mounted for reciprocating and rocking movements, a rotary shaft, gear connections operated by said shaft for imparting intermittent reciprocating movements to said element at spaced intervals of time, gear connections operated by said shaft for imparting intermittent rocking movements to said element at spaced intervals of time between the reciprocating movements aforesaid, and means for rotating said shaft to impart a predetermined number of reciprocating and rocking movements to said element.

22. A machine of the character described comprising a support mounted for longitudinal and rocking movements, means for holding an armature core in connection with said support for said movements with said support and for independent turning movements as desired, and mechanisms for imparting longitudinal and rocking movements to said support and thereby to the armature core to wind a wire in the slots of the core.

23. A machine of the character described comprising a shaft, supports in which said shaft is mounted for alternate longitudinal and rocking movements, mechanism for holding a core in different adjusted positions in connection with said shaft to receive different windings, and mechanisms for imparting alternate longitudinal and rocking movements to said shaft and thereby to the armature core to wind a wire in the slots of the core.

24. A machine of the character described, comprising a support for an armature core, mechanism for actuating said support and thereby the armature core to wind a wire in the slots of the core, and mechanism for holding the core in different adjusted positions to receive different windings.

CLAUDE M. McCORD.
